UNITED STATES PATENT OFFICE.

JOHN W. POST, OF NEW YORK, N. Y.

RAILWAY-CAR.

SPECIFICATION forming part of Letters Patent No. 365,939, dated July 5, 1887.

Application filed November 24, 1886. Serial No. 219,797. (No model.)

To all whom it may concern:

Be it known that I, JOHN W. POST, a citizen of the United States, residing at the city of New York, county of New York, and State of New York, have invented certain new and useful Improvements in the Construction of Railway-Cars; and I do hereby declare the following to be a full, clear, and exact description of the same, such as will enable others skilled in the art to make and use the said invention.

This invention relates particularly to improvements upon the car frame and trucks shown and described in Letters Patent No. 15 285,675, granted to me on the 25th day of September, 1885. Among the additional improvements since devised may be named the means employed for uniting the ends of the tubes which form the circular and rectangular frames of the car-body, and, further, to the device for supporting the buffer-springs in position; also, the construction and arrangement of the buffers and couplings, and, still further, to the construction and arrangements 20 of various parts of the car-truck, by which the car, as a whole, is rendered more durable and perfect in its actions; also, the downwardly-projecting flange of the king-bolt, which excludes dust and dirt and otherwise protects 25 the wearing-surfaces.

In the accompanying drawings, Figure 1 is a side elevation of the car trucks and frame complete, showing the connections and arrangement of the principal parts. Fig. 2 is a 30 plan view of the car-frame and one platform, illustrating the arrangement of parts about the ends of the car in connection with one of the platforms. Fig. 3 is a side elevation of one-half of a car-frame, enlarged and partly in 35 section to show the construction of the pedestals and journal-boxes, as well as the method of securing the springs in the longitudinal tubes of the car-frame. Fig. 4 is a transverse 40 section through the car and one of the car-trucks, especially illustrating the construction of the king-bolt and its connections. Fig. 5 is a perspective view of one of the car-trucks, showing the arrangement of the braces in the 45 same. Fig. 6 is a detail view illustrating the 50 method of connecting the ends of the tubes forming the circular and rectangular frames,

as well as their attachment to the central longitudinal tube forming the continuous draw-bar. Fig. 7 shows a bottom plan of the car, one of the trucks in place, the other having 55 been removed. Fig. 8 represents a vertical section through the draw-bar, showing the buffer and buffer-spring, as well as the method of attaching the coupling-hook. Fig. 9 shows the under side of one of the platforms with 60 the coupling-hook and its operating devices. Fig. 10 is a detail, partly in section, illustrating the manner in which the panels or outer covering of the car is applied to the frame.

The principal features of this invention consist in forming the car and truck frames almost wholly of metallic tubes, preferably of milled steel, as combining great strength with small weights, and so arranging the several parts that the car, when inclosed with an 65 combustible covering, shall be practically indestructible, as it cannot be destroyed by fire, and offers the greatest resistance possible for the amount of material employed in its construction to destruction from the crushing effect 70 of collisions or the many accidents to which all cars are liable when in use.

In the drawings, A A represent the two longitudinal tubes which take the place of the plates in an ordinary car-frame, and A' is a 75 central tube placed above and between the tubular plates A A, and connected therewith, at each end of the car, by a transverse metallic plate, A'', to act as an additional support and ridge-piece. Two tubular sills, B B, running lengthwise—one at each side of the car near its bottom—form the outer lower corners of the car, while at a lower level and between them is the strong longitudinal tube B', serving as an additional support to the floor-frame 80 and acting as a continuous draw-bar, to which the coupling-hooks are attached. It will be observed that these six large tubes extend the entire length of the car and present the greatest possible resistance to the crushing effect 85 of a collision. Connecting these longitudinal tubes and taking the place of the floor and side frames, as well as rafters, of the ordinary car, are the rectangular tubular frames or ribs C and the circular tubular frames or ribs C'. The 90 rectangular frames C pass around outside of the sills and plate, but within the ridge-piece 95 100

and continuous draw-bar, while the circular frames C' pass within the sills and plates and outside of the ridge-piece and draw-bar, forming braces at every angle of the rectangular frame, thus stiffening the car-frame against all lateral shocks or forces which would tend to deflect it from a straight line. These rectangular and circular frames have ends *a* on the tubes from which they are formed, united at their lowest joints by being received into suitable orifices in the clamp-pieces D, and are there secured by set-screws, brazing, or other proper means, which shall render the frames and clamp-pieces in effect integral when united. (See Fig. 6.)

15 A large opening through these clamp-pieces between the two frames receives the draw-bar B', thus uniting each set of frames throughout the length of the car with said draw-bar, causing the draft and ordinary buffer strains to be equally distributed through its entire length, and preventing the strains caused by the draft and buffing mechanism from injuring the car, as they do when attached to each end only, as in the ordinary manner of constructing cars.

20 It will be observed that the frames are arranged in sets or groups of three side by side, two of which—namely, the outer ones of each set—are circular, with a rectangular frame placed between them, and they may, if desired, be firmly united to each other at their intersections. The arrangement of the tubes in each may, however, be changed by placing a rectangular one on each side of a circular one, or by forming each set of only one tube

25 of each kind. It will be seen that by this arrangement a large space is left between the sets or groups of tubes, which space serves the purpose of a window-opening, the groups being placed at the proper distance from each other to allow of such use. The platform of the car and boards over the same are supported above by the bent tube E, the ends of which enter the tube A. A and rest in contact with a spiral spring *b*, coiled within each tube and supported by an abutment, *b'*, formed by slipping a short section into the larger tubes and securing it in the proper position by brazing or other appropriate means. These abutments are found to be much better than the simple pin

30 employed for the same purpose in my before-named patent, as they afford a firm support for the spring-coils throughout their whole circumference, and wholly avoid any danger of breaking the springs by compression. An

35 arm, E', is rigidly secured to the middle of the tube and bent upward to bring it into the proper position to enter the tube A', which is provided with an abutment and spring like the tubes A. This upper platform-support, consisting of the bent tubes E and E', is connected to the tubes A and A' by means of pins *a'*, which pass through both the inner and outer tubes, and are of sufficient strength to retain the parts in position under ordinary

40 circumstances; but in case of a collision the bent tube E, coming in contact with another

car, would be forced inward, shearing off the pins *a'* and allowing the force or momentum of the opposing cars to be taken up by the spiral springs *b*, which then act as buffer-springs to resist the shock, and, with the assistance of the devices hereinafter described, prevent further damage. Depending from the tube E are the tubular rods *c* and *c'*, which are connected at their lower ends to the platform F, and thus assist in supporting the same. The frame-work of these platforms consists of the cross-plate F', secured upon the projecting ends of short tubes G G, which enter the ends of the tubular sills B and bear against coiled springs arranged between the ends of said short tubes, and an abutment within the sills, arranged and acting in the same manner as the abutments and springs in the tubular plates, hereinbefore described, an additional connection being made between the short tubes and sills by pins *a'*, said pins being arranged to be cut by the telescoping of the short tubes with the sills in case of a collision, and allowing the momentum of the opposing cars to be expended on the spiral springs inclosed within the tubular plates and sills. A tubular beam, G', slightly curved, extends along the front of the platform and serves as a buffer-beam, as well as a joint of attachment for the supporting-rods *c*, which depend from the bent tube E, connected with the plates. In order to give support to the steps, the rod *c'* is carried down beneath them, bent at right angles to accommodate it to their form, then carried upward through the ends 100 of the beam G', and finally secured to the rod *c* in such a position as to form an outer hand-rail for the steps. It will be apparent that this platform will form no rigid obstacle to the inward movement of the tubes E, E', and G when made necessary through a collision or other accident. A buffer, H, in axial line with the draw-bar, is connected to the tubular extension G" at each end of said draw-bar by a pin, *a''*, which passes through a slot 110 in the stem of the buffer, thus allowing the latter a limited longitudinal movement against a spiral spring coiled in the extension G' and supported in the rear by an annular abutment in the same manner as are the springs *b* in the ends of the tubular plates and sills. These buffers project a short distance in front of the platform and serve all the purposes of the buffers on ordinary cars, and may, if desired, be provided with a socket for the reception of 115 a link and pin-hole to receive a pin to allow coupling to be made with the link and pin now in common use.

The coupling device which I prefer to use, and which is illustrated, together with its operating mechanism, in Figs. 8 and 9 of the drawings, consists of the hook I, pivoted to an extension of the plate F', which is connected directly to the continuous draw-bar B', said hook having a lateral swinging movement 125 within the guide *d*, secured to the under side of the platform. A spring, *d'*, is also secured to

the plate F' and has its free end bearing against one side of the car. By means of this construction it is evident when two cars are pushed together on the same track the beveled ends 5 of the hooks will allow them to pass each other until the hooks engage, in which position they will be retained by the springs d' until released by withdrawing the hooks from their engagement with each other.

10 c I accomplish the disengagement of the coupling-hooks when desired by means of a vertical shaft, I, journaled upon the platform of the car, its upper end provided with a hand-wheel, I', and its lower end projecting beneath 15 said platform and connected by a chain, d', with the coupling-hooks. It is evident that by rotating the shaft J and winding up the chain the hooks will be drawn to one side, and thus disengaged.

20 20 The king-bolts K, by which the car is connected with the trucks, are attached to the draw-bar B' at suitable points, as follows: The upper end of the king-bolt is expanded so as to form a large head with a semicircular 25 groove in its top. This groove receives the lower half of the draw-bar, which is secured therein by means of the cap K', also provided with a semicircular groove to receive the upper half of the draw-bar, and secured to the 30 head of the king-bolt by screw-bolts, which cause said cap and head to firmly clasp the draw-bar, and thus retain the king bolt in its proper position with relation to the car-trucks. There is also a depending flange, x, made integral with the head of the king-bolt, which 35 completely overcaps the top of the truck-socket O, thus protecting the bearing-surfaces from the usual accumulation of dust and dirt, not only greatly lessening the ordinary friction, but also the wear of these important 40 connections. These trucks are shown clearly in Fig. 5 of the drawings, and are constructed almost wholly of metallic tubes, the main frame consisting of two tubes, L and L', bent into a 45 rectangular form, their ends united, and one placed above the other. At the sides of the truck the tubes L and L' are separated, so as to form a truss in connection with the space-blocks e and pedestals M M, which act as struts 50 between the upper and lower tubes. The space-blocks e also serve as a means of connecting the bolster-beams N with the side frame. These beams N are placed at a suitable 55 distance apart to receive between them the king-bolt socket O, which receives the king-bolt of the car, and in which it may be retained, if desired, so that the car cannot separate from the truck, by a set-screw, e', or bolt passing through one side of the socket and 60 entering a recess in the king-bolt. This connection of the truck with the car allows both a lateral and vertical movement of the truck with relation to the car, the first of these movements being secured by the turning of the truck 65 upon the king-bolt as a center and the second by the oscillation of the car upon the king-bolt,

the draw-bar forming the journal upon which it rocks. The bolster-beam is further strengthened by the curved brace-bars f f, the ends of which are secured in the pedestals and at mid-length to the bolster-socket, thus forming a strong diagonal bracing for the truck-frame. The pedestals M M are also of tubular form, and in addition to their connection with the truck-frame bars L L' are further stiffened by 70 the longitudinal braces g and h h, the first of which (the brace g) is connected at mid-length to the lower part, L', of the truck-frame, its ends bending downward and uniting with the pedestals at their lower ends, the whole forming a stiff longitudinal bracing for the truck-frame as well as the pedestals. The pedestals are slotted on the inner side to allow the passage of the ends of the car axles P P, the journal of which rests in the boxes i i, which 80 in turn support the weight of the truck-frame and car through the springs s, which are placed within the pedestals between the lower bar of the truck-frame and the axle-boxes. 85

In order to prevent the axle-boxes from falling out of the pedestals when the truck-frame is, for any purpose, raised or taken off the track, short sections of tube m m are secured in the lower end of the pedestals by set-screws n n, readily removable when it is desired to 90 change the axle or remove them for other purposes.

In order to give side bearings or supports to the car to prevent excessive oscillation, upwardly-projecting steel bearings r r are secured to the upper bar, L, of the truck-frame 95 upon each side of the truck. The upper ends of said steel bearings enter the curved and grooved wear-plates g g, secured upon the bottom of the car, and not only steady the same, 100 but assist in carrying its weight, thus relieving to a certain extent the load upon the king-bolt socket. The downwardly-projecting flanges of the wear-plate protect the engaging 105 surfaces from the dust and dirt, and thereby 110 greatly lessen the friction in turning curves.

In Fig. 10 of the drawings I have shown the method of attaching the covering of the car to the frame-work; but as this covering forms the subject of a separate application for 115 patent it is not necessary to further describe it here. The car frame and trucks, as will be seen by this description, are composed almost entirely of metallic tubes, thus presenting the metal in that form which experience has demonstrated as affording the greatest strength for a given weight of metal, and the parts are 120 so arranged and proportioned as to avoid an excess of strength and consequent increase of weight in any one part over the rest, thus 125 forming as a whole the lightest running-gear and car-frame in proportion to its strength that can be constructed from the same weight of metal.

Having thus described my invention, I claim 130 as new and desire to secure by Letters Patent the following:

1. As an improvement in car-frames, the combination of the tubular plates and sills with the groups of the tubular rectangular and circular frames or ribs and the continuous tubular draw-bar connected with said frame, as set forth. 40
2. In a railway-car frame, the combination of the groups of tubular rectangular and circular frames with the continuous tubular draw-bar, substantially as specified. 45
3. In a railway-car frame, as a means of uniting the ends of the tubular frames and said frames with the draw-bar, the coupling-piece D, provided with suitable openings to receive 50 said frames and draw-bar, as shown and described.
4. In a railway-car, the tubular continuous draw-bar B', in combination with telescopic extension-pieces G" and buffer H, arranged and 55 operating substantially as set forth.
5. In a railway car, the tubular continuous draw-bar B' and telescopic extension-pieces G", in combination with the hook-couplings I and their operating mechanism, substantially 60 as specified.
6. In a railway-car, the platform F, partially supported by the roof-framing, in combination with the rods c and c', connecting said platform with the roof-frame, and also forming a support 65 for the steps and a hand-rail, as set forth.
7. In a railway-car, the platform F, connecting-plate F', and beam G', in combination with the telescopic extension-tubes G, the spiral springs, abutment-rings, and tubular sills B B, arranged, as shown and described, to act as an 70 additional buffering mechanism and to prevent danger from collisions, as specified.
8. A railway-car provided with grooved 75 wear-plates g, in combination with the steel bearings r, projecting upward from the side frames of the truck and entering the grooves of the wear-plates, as set forth.
9. In a car-truck frame, the combination of the tubular rectangular frames L L', pedestals M, and braces g and h, arranged, as shown and 80 described, to stiffen the truck-frame and support the pedestals.
10. In a car-truck, the combination of rectangular frames L L', bolster-beams N, king-bolt socket O, and braces f, all arranged to support and brace the king-bolt socket, substantially as specified. 85
11. In a railway-car, the king-bolt K, provided with a recess, as described, in combination with the socket O and set-screw e', arranged to prevent the withdrawal of the king-bolt from the socket, as set forth. 90
12. In a railway-car, the king-bolt K, in combination with the cap K' and draw-bar B', arranged to connect the king-bolt directly to the draw-bar, as set forth. 95
13. In a railway-car, the king-bolt secured to the draw-bar, as shown and described, and provided with the downwardly-projecting flanges x, as and for the purpose specified. 100
14. The combination of the king-bolt K, having the downwardly-projecting flanges x, with the king-bolt socket O, carried by the bolster-beam N N upon the truck-frame, as set forth. 105

In testimony that I claim the foregoing as my invention I hereby affix my signature in the presence of two witnesses.

JOHN W. POST.
